[57] CLAIM

The ornamental design for mobile center form, as shown and described.

DESCRIPTION

FIG. 1 is a perspective view of a mobile center form showing my new design;

FIG. 2 is a top plan view thereof;

FIG. 3 is a side elevational view thereof;

FIG. 4 is a bottom plan view thereof;

FIG. 5 is a side elevational view thereof;

FIG. 6 is a side elevational view of the mobile center form with the upper surface of the form disposed to the left; FIG. 7 is a side elevational view of the mobile center form with the upper surface of the form disposed to the right; FIG. 8 is an exploded perspective view of a modified embodiment of a mobile center form showing my new design; and,

FIG. 9 is a perspective view of FIG. 1.

The broken line showing of the mobile components in FIGS. 8 and 9 is for illustrative purposes only and forms no part of the claimed design.
